INFINITE STAGE PUMP

David Grant, Los Angeles, Calif., and
Nicholas Bashark, Dayton, Ohio

Application January 3, 1947, Serial No. 719,974

1 Claim. (Cl. 103—38)

(Granted under the act of March 3, 1883, as
amended April 30, 1928; 370 O. G. 757)

1

The invention described herein may be manufactured and used by or for the Government for governmental purposes without payment to us of any royalty thereon.

This invention relates to hydraulic pumps, and particularly to mechanism for effecting infinitesimal variation of pressure and volume in inverse ratio.

An object of the invention is to provide a hydraulic pump whereby a relatively uniform power input stroke will deliver a progressively decreasing volume at a proportionately increasing pressure.

Another object of the invention is to provide a pump of this character with operating leverage, the mechanical advantage of which increases by infinitesimal increment as the volume required diminishes and the pressure required increases.

In the master cylinder of a hydraulic brake system, braking is accomplished by actuating the master piston through a single stroke, and in such a system it would be highly advantageous if, during the first part of its stroke, the master piston would deliver a relatively large volume of fluid at a low pressure and thereafter progressively decrease the volume and correspondingly increase the pressure throughout the remainder of the stroke without, however, increasing the actuating effort.

It is therefore another object of this invention to provide a mechanism of this character in which the master cylinder on the discharge side of the master piston is connected to a hydraulically operative device for increasing the mechanical advantage of the actuating pedal as the pressure toward the end of the stroke becomes greater and the volume of fluid required becomes less.

Other objects, advantages and meritorious features will become evident as the invention is described in detail with reference to the drawings, wherein,

Fig. 1 is an axial section taken at 1—1 of Fig. 2 through a pump suitable for actuating a hydraulic ram or similar device and made in accordance with my invention.

Fig. 2 is an axial section taken at 2—2 of Fig. 1.

Fig. 3 is an axial section through a master brake cylinder and piston equipped with an embodiment of my invention.

Fig. 4 shows an antifriction bearing which may be employed in my mechanism.

Like reference characters refer to like parts throughout the several views.

Referring more particularly to Fig. 1, a pump cylinder 10 with piston head 12, piston rod 14, suction intake valve 16, and discharge valve 18 is of substantially conventional design, fluid entering at 20 and being discharged at 22. The piston 12 and rod 14 are provided respectively with packings 24 and 26. The suction intake valve 16 and the discharge valve 18 are provided respectively with closing springs 28 and 30. For purposes of description, the piston head 12 and piston rod 14 may collectively be referred to as the piston 15.

15 An auxiliary cylinder 32 is carried on the pump cylinder 10, the axes of the two cylinders being substantially normal one to the other. A bracket 34 joins the two cylinders 10 and 32 to maintain them in fixed relation.

20 Auxiliary cylinder 32 is slidably fitted with a piston head 36 having a piston rod 38 which has sliding bearing in a plug 40 which is in threaded engagement with the cylinder at 42. A compression spring 44 is interposed between the piston 36 and nut 40, the stress of the spring 44 being adjustable by means of the nut 40. A vent 45 is provided to allow air to escape from the spring chamber. A slot 46 is provided in the nut 40 for adjustment thereof. A packing 48 is provided 25 for the piston head 36. For purposes of description the piston head 36 and the piston rod 38 may collectively be referred to as the piston 41. The discharge space 35, to the right of the piston 12 in the main cylinder 10 is connected to the space 37 under the piston 36 in auxiliary cylinder 32 by a passageway 39.

30 The outer ends of the main piston rod 14 and the auxiliary piston rod 38 are respectively forked as at 50 and 52 (see Fig. 2), and between the 35 prongs of the forks lies a hand lever 54. The lower end of the hand lever 54 is hinged to the upper end of the piston rod 38 by a pin 56. A second pin 58 carried in the prongs of the fork 50 passes through a slot 60 in the hand lever 54. Obviously the raising or lowering of the piston rod 38 changes the ratio of the power arm X to the work arm Y of the hand lever 54.

35 Assuming for illustrative purposes only, that the pump shown in Figs. 1 and 2 is about to be used for operating a hydraulic jack which is to raise a relatively heavy weight, and that the top

of the jack ram happens to be somewhat below the weight which is to be lifted.

When pumping starts, the auxiliary piston 36 will be all the way down and the top of the slot 60 will be resting on the pin 58. Since, at the beginning, the weight of the jack ram only is to be lifted, the auxiliary piston 36 may remain at the bottom until the top of the jack ram encounters the weight.

As the slack begins to be taken up, however, the resistance, and consequently the discharge pressure, in the space 35 of the pump increases gradually, and is transmitted through the passageway 39 to the space 37 which raises the auxiliary piston 36 against the resistance of the spring 44, thereby altering the ratio of X to Y , whereby the stroke of the upper end of the hand lever 54 and the force necessary to be applied thereto remains substantially the same whether pumping a large volume against a low pressure or a small volume against a higher pressure.

The exemplification shown in Fig. 3 is particularly applicable to a hydraulic brake. It includes a master cylinder 62, piston 64, piston rod 66, and brake fluid supply tank 68 with port 70 connecting the tank and cylinder. The piston rod 66 is slidably fitted to a nut 72 which is in threaded engagement with the cylinder 62 and is slotted at 74 for a wrench. A vent 75 is provided for allowing air to escape from between the piston 64 and nut 72. A spring 76 lies between the left end of the piston 64 and the end of the cylinder 62 urging the piston rightwise. An outlet port 78 is provided for fluid connection to the brakes or other device being operated. Packings 80 seal the piston 64 against leakage.

The auxiliary cylinder 82, substantially like that shown in Fig. 1 is carried on the master cylinder 62, the axes of the master and auxiliary cylinders being at right angles one to the other. A bracket 84 joins the cylinder 62 and 82 in fixed relation.

Auxiliary cylinder 82 is fitted with a sliding piston 86 having a piston rod 88 which has sliding bearing in a plug 90 which is screwed into the cylinder 82 by means of a suitable wrench which may be fitted to the slot 92. A compression spring 94 urges the piston 86 downward, the stress in the compression spring being adjustable by means of the nut 90. A vent 95 allows air to escape from the spring chamber. A packing ring 96 seals the piston 86 against leakage. The discharge space 98 to the left of piston 64 is connected to the space 100 under the piston 86 by a passageway 102.

The outer ends of the main and auxiliary piston rods 66 and 88 are respectively forked at 104 and 106, a foot pedal 108 lying between the prongs of the forks. The lower end of the foot pedal 108 is hinged to the upper end of the piston rod 88 by a pin 110. A second pin 112 carried in the prongs of the fork 104 passes through a slot 114 in the foot pedal 108. Raising or lowering of the piston rod 88 changes the ratio of the power arm X' to the work arm Y' of the foot pedal 108. The brake actuating mechanism of Fig. 3 operates substantially like the pump described with reference to Fig. 1 except that a complete brake actuation is accomplished by a single stroke of the foot pedal 108.

When a brake actuation starts, the first portion of the stroke is used in bringing the braking surfaces into engagement which obviously requires little force applied to the pedal 108. The auxiliary piston 86 will therefore be at the bottom of

the space 100 and the top of the slot 114 will be resting on the pin 112.

After the braking surfaces have been brought into contact, however, the pressure will be further increased but preferably somewhat gradually so that deceleration may be not too rapid. Now in conventional braking devices this pressure would be increased wholly by increasing the foot pressure on the pedal 108, while in the braking device of Fig. 3, substantially the same pressure on the foot pedal 108 throughout its stroke will gradually increase the pressure on the braking surfaces to a high value because of the transfer of fluid under pressure through the passageway 102 which raises the auxiliary piston 86, thereby gradually changing the ratio of the power arm X' to the work arm Y' .

Fig. 4 illustrates a means of reducing the bearing friction on slot 60 of the hand lever 54 or slot 114 of the foot pedal 108. Here a fitting 116 is placed over a pin 115 and a slot 119 is made somewhat larger as at 118. The fitting is provided with needle bearings 117 on the surfaces that mate with the faces 118 of the slot 119. The contact area of fitting 116 is itself relatively large which reduces the unit pressure. This coupled with the use of the needle bearings reduces friction and wear.

Devices made in accordance with this invention have many advantages. A pump which includes this invention will have a high volumetric output when low pressure only is required but will automatically reduce the volume when pumping against increased pressure, without, however, lengthening the stroke of the operating lever or increasing the force applied thereto.

Since the output of the pump Figs. 1 and 2 is always inversely proportional to the pressure, much time will be saved in pumping into hydraulic devices in which a considerable portion of the cycle of operation is at very low pressure.

The principle of operation, i. e., varying the ratio between the power arm and work arm of the operating lever is more simple than in any multi-stage pumps heretofore known.

The invention is readily applicable to hydraulic brakes and the like, an example of which is seen in Fig. 3. Since the greater portion of the total operating cycle is at very low pressure and consequent high volume, much of the operating stroke of the pedal remains for applying the remaining small volume at very high pressure, and this without increasing the foot pressure on the pedal as is required in brake systems of common practice.

Inasmuch as a braking unit as seen in Fig. 3 automatically adjusts itself to an X/Y position which is commensurate with the need in any case, it follows that the same unit may be used for a wide variety of applications without adjustment.

Having described several embodiments of our invention, we claim:

In a device of the character described, a main cylinder, a main piston slidable axially in said main cylinder dividing said main cylinder into suction and discharge chambers, an auxiliary cylinder, an auxiliary piston slidable axially in said auxiliary cylinder, the axes of said cylinders being substantially at right angles to each other, a lever of the second class, a guide slot in said lever intermediate the ends of said lever extending lengthwise thereof, load transmitting means hinged on the outer end of said main piston slidably fitted to said slot, whereby said lever is slide-

ble bodily endwise along said load transmitting means, a fulcrum means connecting the end of said lever to the outer end of said auxiliary piston, whereby said lever may be moved bodily by said auxiliary piston toward or away from the axis of said main piston, spring means urging said auxiliary piston axially away from the axis of said main cylinder, and a passageway connecting the high pressure side of said main piston to the inner end of said auxiliary piston.
